(57) **CLAIM**

The ornamental design for a table base, as shown and described.

DESCRIPTION

FIG. 1 is a perspective view of the table base of the present invention showing my new design;

FIG. 2 is a top plan view thereof;

FIG. 3 is a front and rear elevational view thereof;

FIG. 4 is a side elevational view thereof; and,

FIG. 5 is a bottom plan view thereof.

The broken lines shown in the figures illustrate environmental structure and form no part of the claimed design.

1 Claim, 3 Drawing Sheets

FIG. 1

FIG. 2**FIG. 3**

FIG. 4**FIG. 5**
